UNITED STATES PATENT OFFICE.

FRANK J. STEPHAN, OF CHICAGO, ILLINOIS, ASSIGNOR TO H. B. ROUSE & COMPANY,
OF CHICAGO, ILLINOIS, A CORPORATION OF ILLINOIS.

SHAVING PLANE.

Application filed December 17, 1926. Serial No. 155,460.

My invention relates to shaving planes and has for its general object the provision of a construction which will more readily permit of the accurate finishing or machining of plane portions hitherto difficult of access to for this purpose.

My invention finds an important embodiment in a plane in which the bit or knife carrying stock is assembled with a guide for directing its movement, such guide directing the plane of movement of the work engaging face or sole of the stock. In a plane of this character a handle is employed for reciprocating the bit carrying stock of the plane, the handle, the stock, and the mounting for the stock upon which the handle is pivoted, cooperating to direct movement of the stock independently of the work. In hand planes, the sole of the stock is generally positioned by the work itself, the sole of the stock being substantially in one plane. Where the stock is guided, it may be preferred to have the trailing portion of the stock sole slightly offset, toward the work, from the leading portion of the stock sole, though the invention is not to be thus restricted. These two portions of the sole of the stock are defined by means of a transverse slot through which the cutting end of the knife or bit slightly projects. It is important to have the front edge of the slot, that slot edge where the bit end is located, accurately machined into exact parallelism with the bit end.

Hitherto, the narrowness of the slot prevented the use of a desirable machining tool for this purpose. In order that access may be afforded to this slot edge, I make the trailing portion of the sole of the stock separately from the balance of the stock and assemble the same with the stock after the desired machining has been performed. The absence of the trailing portion of the stock sole during the machining operation also facilitates the planing of the inclined end surface of the stock against which the bit is held and along which the bit is moved in being adjusted.

The invention will be more fully explained by reference to the accompanying drawing in which Fig. 1 is a side view of the preferred embodiment of my invention as employed in a metal plane, that is, a plane for shaving metal; Fig. 2 is a sectional view on line 2—2 of Fig. 4; Fig. 3 is a perspective

view showing the stock removed from its guide, the trailing portion of the sole of the stock being broken away and the knife or bit of the plane being shown on one side; and Fig. 4 is a plan view of the plane.

The stock 1 of the plane is formed with a transverse slot 2 therethrough through which the cutting end of the knife or bit 3 projects beyond the bottom or sole of the stock a distance corresponding to the thickness of the shaving which is to be removed from the work. The plane bit is held in its selected adjustment against the top end 4 of the stock by means of a clamping bolt 5 whose stem is screwed into the block and whose head 5' clamps the washer 6 against the top surface of the bit to clamp the bit against the top surface of the stock end 4. The surface of the stock end 4 which is engaged by the bit is usually inclined so that the knife is presented at the proper angle to the work for cutting shavings therefrom and for directing the shavings through the slot into the hollow portion 7 of the stock. When it is desired to readjust the plane bit, said bolt 5 is loosened whereupon the bolts 8 are suitably turned. These bolts are screwed into the stock end 4 and have flange enlargements 9 which enter a slot 10 in the bit 3 whereby longitudinal movement of the bit is forced when these bolts are turned, the bolt 5 passing through an elongated slot 11 in the bit which permits longitudinal adjustment of the bit. After the bit has been suitably adjusted, the bolt 5 is tightened to hold it in selected adjustment.

In the embodiment of the invention illustrated, the stock of the plane does not directly carry a handle, the handle 12 for operating the plane stock and the bit carried by the stock being mounted to turn upon a block 13 which, itself, is mounted to turn upon the mounting 14, which is provided upon the guiding frame 14', the axes of movement of the handle upon the block 13 and of the block 13 upon the handle upon the mounting 14 being perpendicular to each other so that the union or joint between the handle 12 and the mounting 14 is universal. The handle has a disc-like or cylindrical enlargement 15 which is received between the body of the stock and the shoulders 16 so that the stock may readily be moved up and down and may be pressed, during such movement, against the work which is located upon the bed 17 that is

carried by the mounting 14 and angular to the stock 1 and its plane of movement. The work is held against the leading portion of the sole of the stock, that which is in advance 5 of the cutting edge of the bit, by means of the block 18 and the rack 19, fixed upon the bed 17, said block being held in relation to the rack by means of a holding dog 20 which is pressed toward the rack by a spring 21 and 10 which may be released from engagement with the rack by means of a thumb piece 22 which is carried upon the rod 23 on which said dog is carried. The spring 21 presses upon the thumb piece 22 in a direction to engage 15 the holding dog 20 with the rack 19 when the teeth upon the dog are in register with teeth upon the rack. When the dog is engaged, said spring is, incidentally, expanded, sufficient power remaining in the 20 spring after the thumb piece 22 is released to engage the holding dog, as stated. The stock of the plane is disposed in an upright groove that is formed in the guide 14', the opposing walls of this groove being recessed 25 as indicated at 24 to receive the stem portions of the T-shaped sides 25 of the stock.

Hitherto, it was somewhat difficult to machine the surface of the stock end 4 which engaged the bit 3 on account of the presence 30 of the trailing portion of the sole of the stock. It was even more difficult to apply the machining tool to the leading edge of the slot 2, that edge which is in advance of the plane bit 3, for the same reason. To obviate 35 this difficulty, I form the trailing portion 26 separately from the balance of the stock and do not assemble it in position until after the desired machining has been accomplished. The trailing portion in the form of a bar 26 40 may be suitably assembled with the balance of the stock as by means of the screws 27 which enable this trailing portion to be removed if it should ever be desired to remachine the leading edge of the slot 2 and the 45 surface of the stock end 4 that is engaged by the bit 3.

The rack 19 is shown as being carried upon a quadrant 28 which may be swung to change the angularity of the work which is pre-

sented to the plane. The quadrant may be 50 held in position by means of the swinging bolt structure 29 passing through a slot 30 in the bed 19'. Said quadrant and the parts 55 in association therewith form no essential part of my invention. It is to be observed by reference to Fig. 3 that the longitudinal side portions of the stock are continued so as to constitute trailing portions thereof that are integrally formed with the stock and in 60 which trailing portions notches are formed to receive the separately formed trailing portion 26. In the machining operation, the trailing portion 26 is removed in order that the machining may be accurately effected. Such machining is continued upon the trailing side portions of the stock so that the rule 65 being operated upon is uniformly positioned with respect to the stock whether the rule laps the slot 2 or not or only partially laps the slot. This structural characteristic 70 makes it unnecessary to exercise any particular degree of care in positioning the work with respect to the stock. Aside from these advantageous characteristics the trailing side portions of the stock form with the body of 75 the stock a U-shaped member whose sides are notched to receive the bar 26 which is thus very accurately positioned with respect to the stock and particularly with respect to a portion of the stock against which the rule 80 being operated upon bears or is pressed.

Having thus described my invention, I claim:

A plane including a stock having a trailing portion of U-shape integrally formed 85 with the balance of the stock and whose longitudinal sides are formed with notches spaced apart from the base of said U-shaped trailing portion; a bar located in said notches and spaced apart from the base of said U- 90 shaped portion to afford a slot through the sole of the stock; and a bit assembled with the stock and having its cutting edge projecting through said slot.

In witness whereof, I hereunto subscribe 95 my name.

FRANK J. STEPHAN.
